UNITED STATES PATENT OFFICE.

HASSELTINE M. DICKINS, OF BROOKLYN, NEW YORK.

STUFFED FIGURE TOY.

Application filed May 7, 1927. Serial No. 189,625.

This invention relates to toys and more particularly to those simulating objects of nature, such as raccoons and the like.

A primary object of the invention is to so construct a toy of this character that it will not only have the appearance of a live animal, but will also have a life-like feeling to the touch.

Another object is to construct a unique toy animal that when placed in any desired position and the various members thereof desirably moved, they will remain as placed and which will yet be jointless having no pivotally connected parts.

Another object is to so construct such a toy that it will have no breakable parts and the stiffening means for which will not penetrate the covering and present objectionable points such as would injure small children, said stiffening means being pliable and thus bending upward in the animal when subjected to pressure whereby the penetration of the covering is avoided.

To accomplish such formation of the toy the invention has in view the construction whereby the body and limbs will be yieldable and flexible and yet sufficiently rigid to remain in the position placed.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a perspective view of the toy completed;

Figure 2 is a perspective view of the wire frame or skeleton detached;

Figure 3 is a longitudinal section showing the interior;

Figure 4 is a plan view of the blank from which the inside portion of the front leg is formed;

Figure 5 is a similar view of inside portion of hind leg;

Figure 6 is a plan view of the front paw facing;

Figure 7 is a similar view of rear paw facing;

Figure 8 is a plan view of the insert used for the top of the head and the rump;

Figure 9 is a similar view of the throat insert;

Figure 10 is a plan view of the blank used in forming the tail, and

Figure 11 is a similar view of one of the ear blanks.

The toy constituting this invention is shown in the form of a raccoon constructed of an outer covering or hide 1, made of long pile fabric to represent fur which is suitably treated and colored and marked to present the appearance of a coon's skin. This skin-like outer covering 1 is suitably shaped, to form, when stuffed, a life-like representation of a raccoon and is preferably constructed as shown in the accompanying drawings being composed of two body members 2 cut out as shown in Fig. 3 of the drawings, and these members are exactly alike, hence one only is shown in the drawings. This member 2, when the animal is to be in the form of a raccoon is cut as shown in Fig. 3 with the inside forelegs 3 and the inside hind legs 4 made integral with the body portion, as is also the front and rear paws 5 and 6. The head 7 is also made integral with the body portion 2 and is notched at the front and rear portions as shown at 7^a and 8^a to indicate the points where the top member 9 shown in Fig. 8 is to be inserted. A member similar to the member 9 used for the top of the head is also used at the rump, which is notched at 9^a to indicate the point of insertion of the rump portion. It will thus be seen that by making this member 9 so that it may be used for both the top of the head and for the rump a single machine may be employed for cutting out these pieces. In assembling the parts the two members numbered 2 are seamed together along the upper portion of the back between the notches 8^a and 9^a. The lower portion of the body members 2 are rounded or convexed at their edges as shown at 2^a and slits 2^b formed at the rear portion of the front leg 3 and the front portion of the rear leg 4 between them and the body to provide flaps 10 which when seamed together in the assembly form the belly of the animal.

A throat piece 11 shown in detail in Fig. 9 is inserted between the members of the head of the animal with its ends 11^a and 11^b registering with the points 7^b and 7^c shown in Fig. 3.

The inside portions of the front legs are cut in separate pieces as shown in Fig. 4 and numbered 12, it being understood that one is cut for the right and one for the left leg. These pieces 12 correspond in shape to the outer portion 3 of the front legs shown in Fig. 2.

The right and left fore-paws are faced with foot portions 13 composed of any suitable material preferably of black flannel, and the hind paws are similarly faced with foot pieces 14.

The inside members of the hind legs are cut in separate pieces as shown 15 in Fig. 5 and are seamed to the outer members 4 of the body portion 2.

10 After the members above described have been assembled by stitching in the manner set forth, the body, legs, nose and head are stuffed in a manner presently to be described.

The tail is next formed from the blank 15 shown at 16 in Fig. 10 and after being stuffed lightly with raw cotton, cotton batting being preferably used, the tail is sewed to the body at the usual place, marked 16' in Fig. 3.

The ears are made from the blanks shown 20 at 17 in Fig. 11 and each comprises two of said blanks seamed together, one having the furred portion of the fabric outside and the other having the backing so as to form the inside of the ear, having the appearance of 25 the natural skin. These ears, after being seamed together are shaped and attached at the points marked 17' in Fig. 3.

Within the skin-like covering formed as above described, is arranged a skeleton frame 30 20 composed of pliable copper wire number 14, rubber single braid covered being preferably used and which is practically indestructible by bending and the like so that no sharp ends will be projected, such as would 35 scratch or injure the person handling the toy.

This frame is formed of two strips of single wire 21 and 22 of a length suitable to form the backbone or body reinforce and the bone substitute for the legs and paws.

40 These strips 21 and 22 are arranged parallel with each other in close proximity and suitably secured together for a length sufficient to form the backbone 23, said wires being preferably tied together for this purpose by

45 wrapping with a single fine covered wire as shown in Fig. 2. The connected portions extend substantially throughout the length of the body, as is shown in Fig. 3 and in dotted lines in Fig. 1 to form the backbone 50 of the animal. This formation of the frame in the manner above set forth adapts it not only to be pliable and crushable but imparts to the toy a dancing springy motion.

The ends of these wires 21 and 22 diverge 55 to form the front and rear leg members of the skeleton, the front members being designated 24^a and 25 and the rear members 26 and 27.

To the lower or foot portion of each leg 60 wire 24, 25, 26 and 27 are secured two curved wire strips 28 and 29, said strips being preferably attached intermediate their length by tying to their respective leg members at a point spaced from their terminals.

65 These wires 28 and 29 as well as the terminals

of the leg wires before being secured together are tightly wrapped with thin cotton batting.

The ends of the wires 28 and 29 and the terminals of the leg wires are located within 70 the feet of the animal and form the stiffening members or bone substitutes for the five toes of each foot, as is shown clearly in Fig. 3, the ends of the leg wires extending into the middle toe.

The nose 18 is suitably stuffed, preferably with cotton batting while the head 7 is filled with cotton wrapped excelsior. This combination of excelsior covered with cotton produces the life-like feeling peculiar to the 80 toy. The legs are similarly stuffed with the cotton wrapped excelsior and the paws are lightly stuffed with cotton.

In stuffing the trunk or body of the animal first a layer of cotton batting numbered 30 85 and about two inches in thickness, more or less, is placed inside against the back of the skin-like covering; then the backbone 23 of connected wires is placed in position and a comparatively large roll 31 of excelsior covered loosely with raw cotton is inserted below the backbone 23 and forms the abdominal 90 filling for the trunk.

To form the legs of the animal the pliable rubber covered copper wire ends 24, 25, 26 95 and 27, are wrapped first with excelsior and then with cotton as is shown clearly in Fig. 3, whereby not only the life-like feeling is produced, but the legs are rendered resilient as well as pliable so that the animal may have 100 a springy movement and yet be compressed into any shape by the baby when hugging or squeezing it and afterward be straightened out into normal shape without having been in any way injured and without in any way 105 injuring the child.

As above described the tail is lightly stuffed with cotton to insure lightness combined with the necessary weight.

The eyes 19 are made of glass beads or 110 buttons having attaching shanks or eyes for the passing of a thread which is extended through the head to the under throat and pulled tight and fastened, which draws the eyes into the head and imparts the deep-set 115 peculiar to coons' eyes.

Feelers 33 are sewed on each side of the mouth which, together with the nose, is indicated by any suitable means, embroidery 120 stitches being here shown.

From the above description, it will be seen that the toy animal constructed as herein shown and described will not only provide an attractive plaything for children of all ages, but may be used as a novelty for grown-ups as well as for campaign novelties and other purposes.

The toy construction as herein shown and described may be squeezed and roughly handled by babies without danger of hurt- 130

ing them in any way or injuring the toy, and its pliable life-like construction renders it particularly lovable and adapted to be hugged up and squeezed, and when released, 5 will automatically return to normal.

While the toy herein shown is in the form of a raccoon, it obviously may be made in the form of any other desired animal.

While cotton covered excelsior is shown 10 and described as the filling or stuffing for the major portion of the toy, it is to be understood that any suitable filling combining the qualities of yieldability and resiliency may be used, the object being to permit the 15 animal's body to be hugged up and squeezed and which when released will assume its normal shape, said body yet having a life-like feeling to the touch.

Without further description it is thought 20 that the features and advantages of the invention will be readily apparent to those skilled in the art, and it will of course be understood that changes in the form, proportion and minor details of construction may 25 be resorted to, without departing from the spirit of the invention or its scope as claimed.

I claim:—

1. A stuffed figure toy comprising a casing, 30 a filling therein comprising a core of relatively coarse loosely assembled resistance exerting fibers, and a covering for the core of relatively fine fibrous material.

2. A stuffed figure toy comprising a casing having a resilient compressible filling composed of a relatively coarse core of loosely assembled resistance exerting fibers and a relatively soft covering to impart to the figure a life-like feeling to the touch.

3. A stuffed figure toy comprising a casing, 40 a filling therein comprising a core of loosely packed relatively coarse resistance exerting fibrous material, and a covering for the core of relatively fine and soft fibrous material.

4. A stuffed figure toy comprising a casing, 45 a filling therein comprising a core of relatively coarse loosely assembled resistance exerting fibrous material, and a covering for the core of relatively fine loosely assembled fibrous material, and a pliable reinforcing element embedded in the core maintaining the shape of the figure yet permitting a life-like dancing and springing action.

5. A stuffed figure toy comprising a casing having a resilient compressible filling composed of a relatively coarse core and a rela-

tively soft covering to impart to the figure a life-like feeling to the touch, and a frame of pliable connected wires embedded in said core and including a backbone having continuous limb members to provide for the movement 60 and adjustment of the parts in any desired position.

6. A stuffed figure toy comprising a casing having a suitable stuffing, and a frame of pliable wire embedded in said stuffing and 65 formed of parallel wires, a binder wrapped around said wires to connect them and form a backbone, the ends of said wires extending into the limbs of the figure, and reinforcing wires secured to said extending wires. 70

7. A stuffed figure toy comprising a casing having a resilient compressible filling composed of an excelsior core and a covering of cotton, which imparts to the toy a life-like feeling to the touch. 75

8. A stuffed toy figure comprising a casing, an internal frame work, a filling comprising a primary resilient packing material applied to the frame work constituting an embedding for the frame work, and a secondary 80 soft packing material of dissimilar texture applied to said embedding.

9. A stuffed figure toy comprising a casing, a frame of pliable wires located in said casing, and a freely resilient readily compressible filling including loosely assembled resistance exerting fibers arranged in said casing over said frame to impart to the toy a life-like feeling to the touch. 85

10. A flexible stuffed toy having limbs and comprising a casing, a loosely wrapped compressible filling, a frame embedded in said filling, said frame being composed of a plurality of single strand fine copper wires arranged parallel and wrapped together for 90 a portion of their length intermediate their ends to form a reinforcing and rejuvenating member, the ends of said frame extending into the limbs of the figure and being flexible or pliable in all directions. 100

11. A flexible stuffed figure toy including a readily compressible loosely assembled resilient resistance exerting fiber filling to provide for the easy crushing of the toy and to produce a life-like feeling to the touch, and means embedded in said filling to impart a dancing springy movement to the figure and to restore the filling to initial position after being crushed. 105
